(57) **CLAIM**

The ornamental design for an activity tracking pod, as shown and described.

DESCRIPTION

FIG. 1 is a front perspective view of an activity tracking pod showing my new design;
FIG. 2 is a top view thereof;
FIG. 3 is a bottom view thereof;
FIG. 4 is a front elevational view thereof;
FIG. 5 is a back elevational view thereof;
FIG. 6 is a left side elevational view thereof;
FIG. 7 is a right side elevational view thereof; and,
FIG. 8 is a cross section view thereof as referenced in FIG. 2. The broken line showing of structural features is included for the purpose of illustrating non-claimed subject matter and forms no part of the claimed design.
